Primary Examiner — Cynthia R Underwood(74) *Attorney, Agent, or Firm* — Carlson, Gaskey & Olds, P.C.(57) **CLAIM**

We claim the ornamental design for a loom and nestable dual hook, as shown and described.

DESCRIPTION

FIG. 1 is a perspective view of the loom and nested dual hook.

FIG. 2 is a front view of a front side of the loom and nested dual hook.

FIG. 3 is a back view of a back side of the loom and nested dual hook.

FIG. 4 is a first side view a first side of the loom and nested dual hook.

FIG. 5 is a second view of a second side of the loom and nested dual hook.

FIG. 6 is a top view of a top side of the loom and nested dual hook; and,

FIG. 7 is a bottom view of a bottom side the loom and nested dual hook.

The broken and dashed lines in the drawings show unclaimed subject matter, and form no part of the claimed loom design.

1 Claim, 5 Drawing Sheets(56)
